Filed Apr. 25, 1968, Ser. No. 11,626

Term of patent 7 years

Int. Cl. D30—01

U.S. Cl. D30—1

FIG. 1.

FIG. 2.

FIG. 3.

FIG. 4.

FIG. 5.

FIG. 1 is a top plan view of a dog house showing my new design with the door closed;

FIG. 2 is a front elevational view;

FIG. 3 is a side elevational view looking from the left in FIG. 1, and also represents a mirror image of the opposite side of the dog house;

FIG. 4 is a rear elevational view; and

FIG. 5 is a view corresponding to that of FIG. 3, but showing the door open and held open by chains.

The essential feature of my design resides in the solid line portions thereof. The broken-line showing of the chain in FIG. 5 has been omitted from the other views as not being necessary for illustration.

I claim:

The ornamental design for a dog house, as shown and described.
